Primary Examiner — Barbara Fox*Assistant Examiner* — Messina L Smith(74) *Attorney, Agent, or Firm* — Akerman LLP(57) **CLAIM**

The ornamental design for a cookware lid, as shown and described.

DESCRIPTION

FIG. 1 is a perspective view of a cookware lid showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the figures illustrate portions of the cookware lid that form no part of the claimed design.

1 Claim, 5 Drawing Sheets(56)
